Patented Dec. 24, 1974

233,974

COFFEEMAKER

Alice Kiernan, Lewiston, Maine, and Patricia A. Luzier
and Gregory Mirow, Corning, N.Y., assignors to
Corning Glass Works, Corning, N.Y.

Filed Apr. 20, 1973, Ser. No. 353,120

Term of patent 14 years

Int. Cl. D7—02

U.S. Cl. D7—65

Fig. 1

Fig. 2

Fig. 3

Fig. 4

Fig. 5

FIG. 1 is a side elevational view of a coffeemaker embodying our new design, the opposite side being a mirror image.

FIG. 2 is a front elevational view.

FIG. 3 is a rear elevational view.

FIG. 4 is a top plan view.

FIG. 5 is a bottom plan view.

The characteristic feature of the design resides in the particular surface ornamentation shown.

We claim:

The ornamental design for a coffeemaker, as shown and described.
